UNITED STATES PATENT OFFICE.

PAUL ROUGET, OF PARIS, FRANCE, ASSIGNOR TO CIE AME CONTINENTALE POUR LA FABRICATION DES COMPTEURS Á GAZ ET AUTRES APPAREILS, OF PARIS, FRANCE.

TIME GAS-LIGHTING APPARATUS.

SPECIFICATION forming part of Letters Patent No. 743,565, dated November 10, 1903.

Application filed April 24, 1903. Serial No. 154,118. (No model.)

To all whom it may concern:

Be it known that I, PAUL ROUGET, a citizen of the Republic of France, residing at Paris, France, have invented certain new and useful Improvements in Apparatus for Automatically Extinguishing Lights, Whether Gas-Burners, Electric Lamps, or the Like, of which the following is a specification.

This invention relates to an apparatus for automatically extinguishing lights after these have been burning a prescribed time. I will describe the same with reference to the accompanying drawings, which show, by way of example, its application to the extinguishing of gas-burners.

Figure 1 is an elevation, and Fig. 2 a plan. Fig. 3 is an inside view of the casing, the front plate being removed to show the ratchet-wheel and double pawl, and the mainspring being shown in dotted lines. Fig. 4 is a horizontal section of the casing, showing the principal interior parts in elevation.

By means of this apparatus when a gas-jet has been ignited it can be extinguished automatically after it has been burning for a certain number of hours without any personal attention being required for the purpose.

The apparatus is capable of numerous applications, of which the most important is the application to street-lamps.

As is known, the municipal authorities establish for the regulation of street-lighting a table of the hours when the lamps are to be lighted and the time for their extinction. The lighting of the lamps presents no difficulties, as the operatives can easily be obtained and supervised to insure that this is correctly done toward nightfall whether they be the regular servants of the municipality or of the gas-works or persons temporarily appointed for this short service, the lighting of the whole of the lamps having to be effected by a definite time. It is, however, not the same in the case of extinguishing the lamps, which is effected at different times in many towns. The operatives have to keep awake for this purpose, and they require high wages for this night service. On the other hand, the control of this service of extinction is diffi-

cult, and the authorities have no guarantee that the extinction is not delayed one or more hours beyond the tabular time, causing a loss to the gas company in the cases where these are only paid for the particular duration of burning set down on the tables. From these circumstances it will be seen that the automatic light-extinguishing apparatus supplies a real want.

Referring to the drawings, there is mounted on an axis α a quadrant-lever S , having internal teeth gearing with a pinion P , fixed on the axis of the spring-barrel of a clockwork, regulated so that the pinion is made to perform, for example, one complete revolution during the maximum length of time for which the lights are to be kept burning. If the quadrant S has the same number of teeth as the pinion, it will be seen that if the quadrant be turned by hand in the direction of the arrow by pulling at the hook C the gas-supply cock R will be opened and the pinion P in being made to revolve will wind up the spring of the barrel corresponding to the extent to which S is turned. A retaining-pawl within the casing B , which contains the clock-work, retains the spring-barrel in the position into which it has been brought, and the spring in unwinding will move backward by means of the pinion P the quadrant S , which is made to complete such motion at the expiration of the predetermined time, as will be presently explained. In turning the quadrant S by the hook C , as described, an arm m thereof lifts a stud c on a lever fixed to the plug of the cock R , thereby turning the latter into the open position until the stud c engages with a pivoted spring-catch n , and the lever and cock are thereby held in the open position until the catch n is disengaged from the stud c . When this takes place, the cock is rapidly closed by a spring Z , connected to an arm on the cock-plug and tending to turn it in the contrary direction to the lever. The quadrant S has an arm d , which when it is turned in the direction of the arrow f allows the catch n to engage with the stud c of the cock-lever, as described, while when lever S has turned a certain distance in the contrary direction the

arm *d* presses the catch *n* out of engagement with the stud *c*, and the cock *R* is then rapidly closed by spring *Z*, as described. The duration of the burning of the lamps supplied by the cock *R* will therefore depend upon the time occupied by the quadrant *S* and its arm *m* in turning back from the position into which it was raised into that in which the arm *d* effects the release of the stud *c* by the catch *n*.

It will be seen that the clockwork that controls the pinion *P* can be so regulated as, for example, to cause the pinion having fourteen teeth to revolve twice in sixteen hours and to bring the quadrant having twenty-eight teeth back from the point to which it had been turned in the opening movement into its starting position during the same time of sixteen hours. The quadrant has on its outer periphery a series of stepped teeth or notches which are at a gradually-increasing distance from the axis *x*, as shown. It will be understood that if a stop were provided in such a position that one of the teeth would come in contact with it during the upward motion of *S* such motion would be arrested at that point, and by rendering the stop adjustable the opening motion of *S* could be limited to a fraction $\frac{1}{n}$ of its total motion, so that the length of time between the lighting and extinguishing of the lights would then be $\frac{16}{n}$ hours. In the arrangement shown the stop *k* for this purpose is mounted on a slide that can be moved up or down in a groove on the clockwork-casing, being secured in position by a clamping-screw *v*, so that according to the position into which the stop is moved it will arrest the opening motion of *S* sooner or later, as above described. At the side of the stop is provided a graduated scale the divisions of which are marked with different hours of duration of the burning, so that the apparatus can readily be set to extinguish the light at any given time by setting the stop at the corresponding division of the scale. Thus it will be seen that having opened the gas-supply cock for the ignition of the lights one can rely upon these being extinguished at the exact time required by means of this apparatus, while this requires no personal attention at all after having once turned the quadrant *S* for lighting, the clockwork being rewound every time the quadrant is so turned by the action of pinion *P*, as described.

The details of the interior mechanism may be considerably varied. A suitable arrangement is shown in Figs. 3 and 4. The casing *B* incloses a spiral spring *Y*, of which the outer end is fixed to the casing *x*, while the central end is fixed at *y* to the shaft *O*, which carries at its outer end the pinion *P*. This shaft *O* carries within the casing a toothed wheel *Q*, which transmits the movement of the spring by any suitable clockwork (which it is thought needless to illustrate) to an es-

capement. The shaft *O* carries likewise a double arm *T*, at the ends of which are pivoted the spring-pawls *g*, which engage a ratchet-wheel *h*, fixed on the shaft *O*.

Although I have described the action of the apparatus in connection with gas or acetylene lights, it will be evident that it is equally applicable to electric lights, as it is only necessary to substitute for the gas-cock suitable contacts on the supply-circuit and a switch in connection with the quadrant *S*, so arranged as to close the circuit when the quadrant is turned upward and to break the circuit when the quadrant arrives at its original position again.

Having thus described the nature of my said invention and the best means I know of carrying the same into practical effect, I claim—

1. Apparatus for automatically extinguishing lights, comprising in combination a toothed segment-lever, a pinion gearing therewith, a barrel-spring on the axis of which said pinion is fixed so that on turning the segment-lever in one direction it effects the winding up of the barrel-spring which in unwinding turns the segment-lever in the contrary direction, a light-controlling lever actuated to permit the making of the light by the segment-lever when the latter is moved in one direction, a catch device for retaining the light-controlling lever in the lighting position, a device on the segment-lever for releasing the light-controlling lever, and a spring arranged to move the light-controlling lever to extinguish the light when the segment-lever is moved back to its original position by the pinion and barrel-spring. 100 105

2. Apparatus for automatically extinguishing lights, comprising in combination a toothed segment-lever, a pinion gearing therewith, a barrel-spring on the axis of which said pinion is fixed so that on turning the segment-lever in one direction it effects the winding-up of the barrel-spring which in unwinding turns the segment-lever in the contrary direction, a light-controlling lever, a stud on said lever engaging with the segment-lever so as to be turned thereby when the latter is moved in the direction for making the light, a spring-catch for holding said light-controlling lever when brought into the light-making position, an arm on the segment-lever that disengages the catch from the light-controlling lever when the segment-lever is turned back into its original position by the pinion and barrel-spring, and a spring acting on the light-controlling lever so as to move it in the direction to extinguish the light when it is released from the catch. 110 115 120 125

3. Apparatus for automatically extinguishing lights, comprising in combination a toothed segment-lever, a pinion gearing therewith, a barrel-spring on the axis of which said pinion is fixed so that on turning the segment-lever in one direction it effects the winding-up of the barrel-spring which in un- 130

winding turns the segment-lever in the contrary direction, a light-controlling lever, a stud on said lever engaging with the segment-lever so as to be turned thereby when the latter is moved in the direction for making the light, a spring-catch for holding said light-controlling lever when brought into the light-making position, an arm on the segment-lever that disengages the catch from the light-controlling lever when the segment-lever is turned back into its original position by the pinion and barrel-spring, and a spring acting on the light-controlling lever so as to move it in the direction to extinguish the

light when it is released from the catch, said segment-lever being provided with a series of step-like notches on its periphery, an adjustable stop adapted to come in contact with one or other of said notches so as to arrest its opening motion and thereby to limit the time during which the light continues.

In witness whereof I have hereunto signed my name in the presence of two subscribing witnesses.

PAUL ROUGET.
